ROAD WORKING MACHINE

Edward Scheunemann, Mount Clemens, Mich.

Application December 6, 1937, Serial No. 178,322

9 Claims. (Cl. 37—160)

This invention relates to road working equipment and has for its object to provide a machine rapidly convertible either into a road planer of improved design or a shoulder forming machine of improved design.

Another object is to provide a light weight machine mounted on an axle intermediate the ends thereof, the axle having a bend near each spindle thereof whereby it may be rotated to lower and to elevate the frame thereof, the lower position being its working position and its upper position being its carrying or transport position.

Another object is to provide a multiplicity of possible positions which the frame may assume with respect to the roadway in order to accommodate itself to various types of work, these positions being affected by the provision of multiple rotative adjustment of the axle with respect to said frame.

A further object is to provide a draw member pivotally attached to the frame in order that the cutters may freely drag along the ground in combination with means for rigidifying this member with respect to the frame when in carrying position. A specific object is to provide a multiplicity of positions in which the rigidifying means may function whereby the frame may be made to travel horizontally regardless of whether the vehicle by which it is to be transported is relatively high or low.

Another object is to provide blade holders and blades therefor of such construction that they may be shifted longitudinally of their holders in order to alter their positions with respect to the frame side rails thereby lending themselves to use for scraping or for shoulder forming.

Another object is to provide means for adjusting at least one of these blade holders longitudinally of at least one frame side rail whereby it may be given the most advantageous position for the type of work to be performed.

A still further object is to provide a detachable trailer blade holder and blade universally connected near the rear end of one of the frame side rails. This trailer blade has the function of sweeping the hard surfaced road and of completing the shoulder forming operation.

Another object is to provide an improved blade having two cutting edges, one of the edges being straight, the other being serrated in order to more readily cut into hard roads such as oil hardened earth roads. The straight edge may then be used for planing.

Other objects and advantages will hereinafter

become more apparent as reference is had to the accompanying drawings wherein:

Fig. 1 is a plan view of my improved machine with the trailer blade in transport position.

Fig. 2 is a vertical section taken along the line 2—2 of Fig. 1.

Fig. 3 is a view similar to Fig. 2 with the scraper blades in lowered position.

Fig. 4 is a vertical section taken along line 4—4 of Fig. 1.

Fig. 5 is a view similar to that of Fig. 2 showing the trailer blade in operating position.

Fig. 6 is a vertical section taken along the line 6—6 of Fig. 1 with the cutter blade in road planing position.

Fig. 7 is a section similar to Fig. 6 with the blade in shoulder forming position.

Fig. 8 is a vertical section taken along the line 8—8 of Fig. 1.

Fig. 9 is similar to Fig. 8 with one blade section removed.

Fig. 10 is a vertical section taken along the line 10—10 of Fig. 5.

Fig. 11 is a vertical section taken along the line 11—11 of Fig. 1.

Fig. 12 is a view similar to Fig. 11 with the blade shifted to an alternate position, and

Figs. 13 and 14 are diagrammatic plan views of the two arrangements of blades, for use as a road planer or as a shoulder forming machine, respectively.

More particularly 1 indicates a frame having right and left side rails 2 and 3. Secured beneath the side rails by the bolts 4 are blade holders 5, 6 and 7 arranged respectively non-parallel. The blades 8 and 9 are respectively attached to the holders 5 and 7, the holder 6 being equipped with two blade sections 10 and 11.

Journalled in the side rails 2 and 3 is an axle 12 bent at 13 near each end and terminating in spindles upon which the wheels 14 are rotatably mounted.

The frame with its cutter blades is balanced on its journals in such manner that it is slightly heavy toward the front end thereof. Intermediate the side rails 2 and 3 two wheels 15 are fixedly secured to the axle 12. These wheels are serrated at 16 to provide a plurality of gear teeth for a plunger 17 spring pressed at 18 and slidably mounted in an arm 19 journalled on the axle 12 between the wheels 15. The plunger 17, by falling into a space between two teeth 16, rigidifies the arm 19 with respect to the axle so that upon rotation thereof the axle may be caused to rotate thus swinging the arm 13. It

may thus be seen in Fig. 2 that if the axle 12 is rotated clockwise the frame 1 will be elevated whereas rotation of the axle in a counterclockwise direction will cause the depression of the frame 1 toward the ground until contact is established between the ground and the blades 8, 9, 10 and 11.

A draw member 20, the front end 21 of which is adapted for attachment to a truck, a tractor or other prime mover is pivotally connected at 22 to the side rails 2 and 3 so that the frame with its cutters may be dragged along the ground. In order to transport the frame upon elevation thereof by consequence of the rotation of the axle 12 as previously described, the draw member 20 may be rigidified with respect to the side rails 2 and 3 by the insertion of pins 23 through an opening in each rail of the members 20 which align with any one of a plurality of vertically spaced holes 24 in a bracket 25 arising from the front end of the side rails 2 and 3 at their points of attachment to the cross rail 24'. This adjustment permits an angularity between the draw-bar and the frame rails in order that the frame may be maintained horizontal while being transported regardless of variations in height of the vehicle to which it is attached. Arising from the cross member 24' is a rack 26 having a multiplicity of fingers 27 extending outwardly therefrom in vertically spaced relation to serve as means for retaining the arm 19 in any given position. Thus, with the plunger 17 in engagement in the manner illustrated in Fig. 2 the arm may be made to engage any one of a number of the fingers 27 to adjust the height of the frame 1 with respect to the ground, the selection of position being variable by a small amount in order to accommodate the blades to the particular type of work for which they are called upon.

Fig. 3 shows the arm 19 being swung to vertical position in which event the wheels 14 are elevated entirely from the ground and consequently add their weight to the weight of the frame. By moving the finger 17 from the position shown in Fig. 3 to the last notch 16a in the wheel 15 the arm 19 may be made to engage a finger 27 thus retaining the wheels in the position illustrated. If the finger 17 be moved to the other end of 50 the notch portion into engagement with the notch 16b the arm 19 may be made to engage one of the fingers 27 and retain the frame in transport position. Between these two positions numerous adjustments are advantageous depending on the type of work to be done.

Fig. 1 illustrates the machine with the various blades so arranged that the machine is adapted for use as a scraper or planer. The front blade 8 terminates well inside the left side rail 3, the blade 10 extends well outwardly of the side rail 3 and the blade 9 also extends outwardly of the frame rail 3 but to a less extent than the blade 10. This is the conventional arrangement of blades for this type work. In order to convert the machine into a shoulder forming machine the blade 8 is moved longitudinally of its blade holder for an amount such that it terminates immediately below the inside edge of the left side rails 3, the blade 10 is removed leaving only the blade 11 on the inside blade holder 6 and the blade 9 is moved to a position beneath the center of the left side rail 3. The blade holder 7 is shifted in position so that it will assume the position illustrated in dotted line 1a, the position being illustrated in full lines on the diagram

Fig. 14. This requires that the bolts 4 which attach the holder 7 to the rail 2 be removed and that two of them be replaced for engagement with the holes 4a and that the bolts 4 in the member 3 be removed and that two of them be replaced to pass through the holes 4b. Due to the change in angularity of the member 7 with respect to the side rails only two of the bolts will be replaced at each side rail.

In order to permit the shifting of the blade 8 with respect to the holder 5 the blade is secured to the holder by bolts 28 uniformly spaced so that the blade may be shifted a distance equal to one or a plurality of links between both holes. Thus, I have illustrated three different means in the three different instances for changing the position of the left hand end of the blade with respect to the side rails 3. Obviously all blades might be shifted according to the plan in either one of the three different ways illustrated.

The illustration of the blades in their two positions of planing and of shoulder formation is illustrated in Figs. 13 and 14 wherein it is seen that the object of the front planar blade is to scrape the road surface and also to move a portion of the dirt laterally to the left, where it is taken by the intermediate blade and moved transversely of the road, this blade dumping a residue onto the final blade 9, this final blade being slightly elevated with respect to the other two blades by virtue of the fact that the frame normally tilts forward. In Fig. 14 the arrangement shows the front blade in position for planing with the residue being dumped at the edge of a hard surfaced road 29, the intermediate blade acting as a scraper for delivering a quantity of earth to the rear blade 9 which is now turned at such an angle that it accepts all the earth delivered by the blade 11 and transports a certain quantity of it over to the shoulder of the road 29 and actually upon the road 29. In this manner, the operator may be certain that the shoulders immediately adjacent the road 29 are completely built and it remains thereafter to scrape or sweep the road 29 of dirt which has been dumped thereon by the blades 9. In order to accomplish this, I provide a rear trailer blade holder 30 having a blade 31 secured thereto, this blade normally travelling at an angle such that it scrapes any dirt on the road 29 off the side thereof in the direction of the newly formed shoulder. This holder 30 is attached to the left side rail 3 by means of a pin 32 which fits in a slot 33 with sufficient play or looseness to permit a substantial universal motion between the holder and the side rail 3. The holder 30 is thus readily detachable from the side rails 3 or it may be rotated about its pivot 32 through an angle of substantially 180° to a carrying position as illustrated in Figs. 1, 2 and 3.

The blades 8, 9, 10, 11 and 31 are each constructed with two cutting edges, one of the edges being straight whereas the other one is serrated as indicated at 34. The straight surfaces are employed for ordinary planing or scraping work whereas the serrated edges are employed, for instance, on earthen roads hardened by oil applications and having many holes therein. By pulling the machine over these holes with the serrated teeth for one or several times the earth is sufficiently loosened at its surface that when the blades are reversed and the machine then pulled thereover, a smooth surface results.

Various modifications may be made without departing from the spirit of my invention and

I desire to be extended protection within the scope of the appended claims.

What I claim is:

1. A road working machine comprising a frame having cutter blades therebeneath and transversely thereof, an axle upon which said frame is journalled having crank ends and wheels journalled thereon, an arm, means connecting said arm to said axle for the rotation thereof through a substantial angle whereby said frame may be lowered into road working position or elevated to carrying position, said means being adjustable to vary the relationship between the arm and the cranks, and a rack bracket having a plurality of vertically spaced fingers each one of which is adapted to receive and to retain said arm. 10
2. A road working machine comprising a frame having cutter blades therebeneath and transversely thereof, an axle upon which said frame is journalled having crank ends and wheels journalled thereon, an arm secured to said axle for the rotation thereof through a substantial angle whereby said frame may be lowered into road working position or elevated to carrying position, and means for adjusting said arm rotationally about said axle and for holding it relative to the axle in different angular relationships with the cranks. 20
3. A road working machine comprising a frame having cutter blades therebeneath and transversely thereof, an axle upon which said frame is journalled having crank ends and wheels journalled thereon, an arm journalled on said axle, a wheel adjacent said arms and fixedly secured on said axle having teeth formed on the periphery thereof, and a spring pressed finger slidably mounted on said arm into engagement between any two of said teeth whereby said arm may be adjustably fixed to said axle. 30
4. A road working machine comprising a frame having cutter blades therebeneath and transversely thereof, an axle upon which said frame is journalled having crank ends and wheels journalled thereon, an arm secured to said axle for the rotation thereof through a substantial angle whereby said frame may be lowered into road working position or elevated to carrying position, means for adjusting said arm rotationally of said axle to any one of a plurality of positions, and selective means for retaining said arm in any one of a plurality of vertically spaced positions with respect to said frame. 40
5. A road machine comprising a frame having a plurality of transverse, non-parallel blades secured therebeneath, and an auxiliary blade holder having a blade attached thereto pivotally connected to said frame to one side of and near the rear end thereof for swinging movement with respect thereto, said frame and holder having interengaging portions restricting lateral movement of the holder relative to the frame. 5
6. A road working machine comprising a frame having a plurality of transverse, non-parallel blades secured therebeneath, a holder for an auxiliary blade having a blade attached thereto, and hook means detachably securing the holder to the rear end of one side rail of said frame. 10
7. A road working machine comprising a frame having a plurality of transverse, non-parallel blades secured therebeneath, said blades terminating inwardly of the outside edge of the left side rail of said frame, a trailer blade holder having a blade attached thereto, and hook means securing the holder to the rear end of said left side rail, said trailer blade extending to the left of the axis of said left side rail by a substantial amount. 15
8. A road working machine comprising a frame having a plurality of transverse non-parallel blades secured therebeneath, said blades terminating inwardly of the outside edge of the left side rail of said frame, and a trailer blade holder having a blade attached thereto swingably secured to the rear end of said left side rail, said frame and holder having interengaging portions restricting lateral movement of the holder relative to the frame, said trailer blade extending to the left of the axis of said left side rail by a substantial amount, said holder being readily detachable from said left side rail. 20
9. A road working machine comprising a frame having a plurality of transverse, non-parallel blades secured therebeneath, said blades terminating inwardly of the outside edge of the left side rail of said frame, and a trailer blade holder having a blade attached thereto secured to the rear end of said left side rail, said trailer extending to the left of the axis of said left side rail by a substantial amount, said holder being pivoted on said side rail and swingable on its pivot through an arc of about 180° to a carrying position. 25
10. A road working machine comprising a frame having a plurality of transverse, non-parallel blades secured therebeneath, said blades terminating inwardly of the outside edge of the left side rail of said frame, and a trailer blade holder having a blade attached thereto secured to the rear end of said left side rail, said trailer extending to the left of the axis of said left side rail by a substantial amount, said holder being pivoted on said side rail and swingable on its pivot through an arc of about 180° to a carrying position. 30
11. A road working machine comprising a frame having a plurality of transverse, non-parallel blades secured therebeneath, said blades terminating inwardly of the outside edge of the left side rail of said frame, and a trailer blade holder having a blade attached thereto secured to the rear end of said left side rail, said trailer extending to the left of the axis of said left side rail by a substantial amount, said holder being pivoted on said side rail and swingable on its pivot through an arc of about 180° to a carrying position. 35
12. A road working machine comprising a frame having a plurality of transverse, non-parallel blades secured therebeneath, said blades terminating inwardly of the outside edge of the left side rail of said frame, and a trailer blade holder having a blade attached thereto secured to the rear end of said left side rail, said trailer extending to the left of the axis of said left side rail by a substantial amount, said holder being pivoted on said side rail and swingable on its pivot through an arc of about 180° to a carrying position. 40
13. A road working machine comprising a frame having a plurality of transverse, non-parallel blades secured therebeneath, said blades terminating inwardly of the outside edge of the left side rail of said frame, and a trailer blade holder having a blade attached thereto secured to the rear end of said left side rail, said trailer extending to the left of the axis of said left side rail by a substantial amount, said holder being pivoted on said side rail and swingable on its pivot through an arc of about 180° to a carrying position. 45
14. A road working machine comprising a frame having a plurality of transverse, non-parallel blades secured therebeneath, said blades terminating inwardly of the outside edge of the left side rail of said frame, and a trailer blade holder having a blade attached thereto secured to the rear end of said left side rail, said trailer extending to the left of the axis of said left side rail by a substantial amount, said holder being pivoted on said side rail and swingable on its pivot through an arc of about 180° to a carrying position. 50

EDWARD SCHEUNEMANN.
